UNITED STATES PATENT OFFICE.

CHARLES A. FRASER AND FRANK M. HENRY, OF MINNEAPOLIS, MINNESOTA, ASSIGNORS
OF ONE-THIRD TO CRISS K. SPEARS, OF MINNEAPOLIS, MINNESOTA.

MELTING-POT.

1,226,496.

Specification of Letters Patent. Patented May 15, 1917.

Application filed October 19, 1916. Serial No. 128,541.

To all whom it may concern:

Be it known that we, CHARLES A. FRASER and FRANK M. HENRY, citizens of the United States, residing at Minneapolis, in the county of Hennepin and State of Minnesota, have invented certain new and useful Improvements in Melting-Pots, of which the following is a specification.

This invention relates to certain new and useful improvements in melting pots for type casting or type setting machines and it has for its objects among others to provide a simple and cheap, yet efficient and reliable means for automatically feeding molten metal to the regular melting pot.

It has for a further object to provide a device which shall eliminate all lost time of the operator in the care of feeding the machine with molten metal and to keep the metal pot in the casting machine free of dross and all dirt, thus insuring a more perfect slug or cast line.

It has for a further object to do away with the expense of re-casting the used linotype slugs into pigs, thus effecting a considerable saving in labor, time and metal.

It has for a further object to make it easier to keep an even temperature of metal in the casting pot, as the latter will be constantly supplied with hot metal instead of cold metal as has been the practice heretofore.

It has for a further object to provide means whereby the quantity of metal in the auxiliary pot shall have no bearing in the operation of the automatic valve whereby we insure at all times and under all conditions a practically even quantity of metal in the active melting pot.

We so construct and arrange our device that the auxiliary pot shall get the greatest possible benefit from the main gas burner, it being provided with flues to assist in keeping the metal at an even temperature. It also contains a baffle plate against the flues which is so perforated as to permit a flow of pure metal.

We provide also an asbestos lining for the pot so as to retain the heat, also to keep the heat from the operator. We arrange the pot so as to make it easier to fill and easier to remove therefrom any dross which may form on the top of the metal, it being set practically alongside the main pot and a short distance above it.

Other objects and advantages of the invention will hereinafter appear and the novel features thereof will be particularly pointed out in the appended claims.

The invention is clearly illustrated in the accompanying drawings, which, with the numerals of reference marked thereon, form a part of this specification, and in which

Figure 1 is a top plan with parts in section.

65

Fig. 2 is a section on the line 2—2 of Fig. 1, looking in the direction of the arrows, with portions broken away and parts in elevation.

Fig. 3 is a section on the line 3—3 of Fig. 2, looking in the direction of the arrows.

Fig. 4 is an enlarged detail showing the pivoted cam and the co-operating member which controls the valve.

Fig. 5 is a view at right angles to Fig. 4.

Like numerals of reference indicate like parts throughout the several views.

Referring to the drawings,

1 designates a linotype pot which may be of the usual construction with the outlet 2.

60

3 is a float, preferably a hollow brass float, adapted to be supported upon the molten metal within the pot 1. This float is carried by a rod or stem 4, as seen clearly in Fig. 2.

65

5 is an auxiliary melting pot supported adjacent to the active melting pot 1 and provided with a discharge outlet 6 controlled by a valve 7 fitted to a seat 8, as seen in Fig. 2, said seat being at the bottom of the auxiliary pot and the discharge opening 90 6 communicating with a discharge pipe 9 which extends into the pot 1 to a distance below the normal level of the molten metal in said pot 1.

70

The pot 5 has a portion of its wall inclined upwardly and outwardly, as seen at 10, and is provided with a plurality of flues 11, 12 and 13, as seen clearly in Figs. 1 and 2. 14 is a baffle plate extending vertically and bridging the space between the two flues 12 and 13, as seen best in Fig. 1.

75

The auxiliary pot 5 is inclosed within a casing or jacket 15 which is provided with an asbestos lining 16 to retain the heat and to keep the heat from contact with the operator or attendant. This casing or jacket is provided with a door 17 at the top for filling the pot 5 and for ready access for cleaning the type metal when necessary. It is also provided at the side with a door 18 for per- 110

mitting removal of the pot 5 when necessary for cleaning or other purposes. These doors are shown as hinged at 19 and 20 respectively, but it is evident that they may be 5 made otherwise removable.

The bottom 21 upon which the pot 5 is supported by means of the depending tubular extension 22 through which the outlet 6 extends, is provided with an opening 23 beneath which is designed to be placed the burners, gas or any other style, as may be found preferable. Any suitable form of support for the auxiliary pot and its casing may be provided.

15 24 is a vent from the casing 15, as shown best in Fig. 2.

The valve 17 is provided with a stem 25 connected therewith in any suitable manner, as seen at 26, and at its upper end 20 loosely connected with a rod 27, in the present instance the upper end of the valve stem being shown as provided with a lateral extension 28 loosely received within an eye 29 on the lower end of the rod 27.

25 Secured to the outer wall of the casing 15 is an upright 30 on which is pivotally mounted, as at 31, a horizontally disposed arm 32, the opposite ends of which are loosely connected with the rods 4 and 27, as 30 at 33 and 34 respectively. While any suitable form of connection between this cross arm 32 and the rods 4 and 27 may be employed, that shown in Figs. 2 and 4 has been found to be efficient. Provision is made for 35 adjustment of the valve and float by means of the nuts 35 and 36 on the rods 4 and 27 respectively. These nuts also serve to hold the ends of the cross bar 32 against displacement.

40 The baffle plate 14 is provided near the lower end thereof with the holes 37, as seen best in Fig. 3, for the flow of the molten metal from the main body of the pot 5 through the discharge opening 6 when the 45 valve 7 is open and through the discharge pipe 9 into the pot 1.

The cross arm 32 is provided with an upright member 38 in the upper end of which is a V-shaped notch 39 in which engages the 50 point of a pendent swinging member 40 pivotally mounted, as at 41. As seen best in Fig. 5, the upright 30 is divided or composed of parallel spaced members between which the arm 32 and its upright portion 38 55 are mounted.

The upper end of the spaced members of the upright 30 are connected, as by the cross member 42, in which is threaded a member 42^a through which is guided a stem 43 with 60 a set nut 44 to hold the member 42^a in adjusted position. The lower end of the stem bears against the yoke or the like 45, which, in turn, carries the pivot 41 above referred to, a spring 46 being interposed between the 65 said member 42^a and the yoke 45. This

screw provides for adjustment of the tension of the spring and a pivot 41 of the swinging member 40 is disposed in vertical slots 47 in the opposite side bars of the upright 30 and is controlled by the pressure of 70 said spring. The swinging member 40 is designed to give quick snappy action to the valve.

The holes 37 in the baffle plate near the lower end thereof are for straining the type 75 metal before it passes through the valve.

In practice, it is to be understood that the vent or smoke pipe 24 may be connected with a chimney or lead to the atmosphere and the parts are assembled substantially as 80 shown in Fig. 2. Any form of burner may be employed beneath the pot 5, preferably some suitable form of gas burner with a simmierer and pilot light of well-known construction and for an obvious purpose. The 85 metal is supplied to the pot 5 by opening the door 17, the upwardly and outwardly inclined surface 10 of the inner wall of the pot facilitating the same. The float 3 rests upon the molten metal in the pot 1 and as 90 the height of this metal varies from usage the float falling pulls down upon the rod 4 and upward upon the rod 27, automatically lifting the valve 7 from its seat so that molten metal is automatically supplied to 95 the pot 1. When the metal in the pot 1 reaches a predetermined level, the float rises and automatically closes the valve, thus shutting off the flow of the molten metal from the pot 5 to the pot 1. By this means we 100 are enabled to keep practically an even amount of pure metal in the active pot 1 no matter how fast or slow the operator may be and no matter what size of slug is being cast, for the instant the metal in the pot 1 lowers enough to actuate the brass float in 105 said pot, the valve in the auxiliary pot is automatically opened and releases molten metal to take the place of the metal used from the pot 1 so as to fill the latter back 110 to its original quantity when the valve is automatically closed. The spring 46 bearing on the cam 40 gives sufficient pressure 115 to cause the cam to give a quick snappy action to the valve whether it be for its closing or opening movement.

Modifications in details may be resorted to without departing from the spirit of the invention or sacrificing any of its advantages.

What is claimed as new is:—

1. In a device of the character described, a melting pot, an auxiliary melting pot, heating means for the latter, a valve for controlling the flow from the auxiliary melting pot, a float, a rockingly mounted connection between the float and valve and a spring-pressed pivoted pendent member coöperable with said rocking connection to actuate the latter to give a quick snappy action to the valve.

120

125

130

2. In a device of the character described, a melting pot, an auxiliary melting pot, a valve within the latter for controlling the outlet therefrom, and a float in the first-named melting pot operatively connected to move in one direction as the valve moves in the opposite direction and a pendent pivoted member coöperable with the connection between the float and valve to give the latter a quick snappy action.

3. In a device of the character described, an auxiliary melting pot having flues, and a baffle plate bridging the space between two of said flues, said auxiliary melting pot having a discharge in its bottom and said baffle plate having openings near its lower end.

4. In a device of the character described, a melting pot, an auxiliary melting pot, a float in the former, a valve in the latter, rods connected with the float and valve, a cross arm connected with said rods and pivotally mounted between its ends, an upright member carried by the crossarm and having a notch, and a pendent swinging member pivoted above the upright member and having an end engaged in said notch and actuated by the movement of the float to give a quick snappy action to the valve.

5. In a device of the character described, a melting pot, an auxiliary melting pot, a float in the former, a valve in the latter, connections between the valve and float to cause them to move in unison in opposite directions, and a spring-actuated pendent swinging member constructed and arranged to give to the valve a quick action upon movement of the float.

6. In a device of the character described, a melting pot and a float therein, an auxiliary melting pot and a valve therein, connections between the valve and float to cause them to move in unison in opposite directions, a pendent swinging member engageable with a member of said connections, a spring acting on the pendent swinging member, and means for adjusting the tension of said spring.

In testimony whereof we affix our signatures in the presence of two witnesses.
